EDSON RAY WOLCOTT, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA.

ART OF PRECIPITATING SUSPENDED MATERIAL FROM GASES.

1,329,817.

Specification of Letters Patent.

Patented Feb. 3, 1920.

Application filed July 5, 1917. Serial No. 178,838.

To all whom it may concern:

Be it known that I, EDSON RAY WOLCOTT, a citizen of the United States, residing at Los Angeles, in the county of Los Angeles and State of California, have invented a new and useful Improvement in the Art of Precipitating Suspended Material from Gases, of which the following is a specification.

10 This invention relates to the precipitation of dust or fume from gases by the action of an electrical field, and the main object of my invention is to overcome certain difficulties which arise in the precipitation of certain materials, particularly those which are substantially non-conducting under conditions usually existing in processes of this kind.

In the electrical precipitation of suspended material from gases, the process now in general use involves production of an electrical field between one or more discharge electrodes and one or more collecting or receiving electrodes, the electrical field being maintained between said electrodes by applying to said electrodes unidirectional current of sufficiently high tension to produce discharge of electricity from the discharge electrodes in such manner as to charge the particles of suspended material in the gas and cause precipitation of such particles on the collecting or receiving electrodes. In order to insure effective precipitating action, it is usual to make discharge electrodes of such form as to produce a concentrated field adjacent thereto, and to thereby facilitate discharge of electricity therefrom, while, on the other hand, the collecting or receiving electrodes are usually formed with comparatively extended surfaces so as to minimize the field intensity adjacent thereto, and prevent as far as possible, any discharge therefrom. In order to provide for the greatest possible efficiency in precipitation, it is desirable to maintain as high a potential difference between the electrode as possible without causing disruptive discharge or arcing between the electrodes. For this purpose, it is desirable in general to apply the current to the electrodes in such manner that the discharge electrodes are negative, as ordinarily it is possible with this arrangement to maintain a higher potential difference between the electrodes than is practicable with the reverse polarity. In the opera-

tion of precipitating apparatus of this kind, there is, in general, in the case of deposits of solid material, continuous precipitation of the suspended particles on the collecting or receiving electrode under the electrical action and in most cases, the deposit so precipitated tends to remain on the collecting or receiving electrodes until it is forcibly removed by jarring or otherwise.

In the operation of electrical precipitation apparatus, it has been found that as the deposit accumulates on the receiving electrodes, there is, in some cases, a marked decrease in the efficiency of precipitation or the "clearance" of the gas, and this has also been found, in general, to be associated with a decrease in the arcing voltage—that is, the maximum voltage that can be maintained between the electrodes without arcing. This effect varies with the nature, material and condition of the deposit, being especially marked in the case of deposits, such as those of zinc oxid produced in zinc smelting furnaces, wherein the deposit is of poorly conducting material and is of a light porous nature, and the effect also depends on the configuration of the deposit, being increased by any roughness or projection on the deposit tending to produce localization of the electric field, and in this connection, it may be stated that a much slighter degree of roughness or surface projection of any part of the receiving electrode is sufficient to cause break down of the electrical field under given voltage conditions, in case of a poorly conducting deposit than in case of an effectively conducting surface.

Whatever may be the cause of the phenomenon above referred to, it may be stated that it only occurs to a degree sufficient to cause serious lowering of the arcing voltage when the deposit is of non-conducting or poorly conducting material, and I have found that in such cases, normal precipitation conditions may be restored and full electric voltage may be maintained by applying to the deposit a suitable agent which increases its conductivity to a certain extent.

An investigation of the phenomenon herein described has led me to the conclusion that it requires, for its production, a configuration of surface, by reason of roughness or porosity, which leads to local ionization, and that there is also required, a sufficiently low conductivity of the deposited

material to enable the ionization to build up or accumulate an electric charge on the material, which eventually becomes of sufficient intensity to break down the dielectric. As far as I have found, the lowering of the arcing voltage is only marked when the discharge electrode is negative and the effect of the deposit is, in general, to lower the arcing voltage to or toward the limit that could be maintained in case the discharge electrode were positive, and to thus lose the advantages of working with negative discharge electrode as set forth in patent to F. G. Cottrell, No. 1,067,974, dated July 22, 1913.

It may, therefore, be stated that in the case of electrical precipitation of fumes or dust of non-conducting material, there is a tendency to an accumulation of an electrical charge by the deposit produced on the collecting or receiving electrodes and this charge tends to ionize gases in the vicinity of the collecting electrode, with the result that there is a considerable lowering of the voltage that can be maintained between the discharge electrode and the collecting or receiving electrode, and this lowering of the "arcng voltage" considerably decreases the efficiency of precipitation.

My present invention consists essentially in conducting away the electrical charge from the deposit so as to prevent accumulation of charge thereon. I provide for this by applying to the deposit a suitable agent which increases the electrical conductivity thereof sufficiently to prevent accumulation of a charge thereon. My invention may be carried out in various ways as hereinafter described.

A simple and effective way of carrying out my invention is to apply to the deposit, a conducting material which becomes intimately mixed with, or distributed on the deposit in such manner as to render the deposited body of material conducting, as a whole. For this purpose, I prefer to use a conducting liquid, on account of the facility and thoroughness with which a liquid may be distributed in or upon the deposited material. Any conducting liquid may be used, such as a solution, either acid or otherwise, according to the special results desired, or the special conditions of any particular case, but in general, ordinary water is the most available and suitable liquid. Thus, in the case of precipitation of a fume of zinc oxid or other substantially non-conducting material, the resulting deposit may be made conducting in any of the following ways:

Water may be sprayed on to the deposit from suitable spray means located adjacent thereto, and within the precipitating chamber, said spray means being, for example, formed as the discharge electrodes themselves, which may be formed as perforated

pipes through which the water may flow; or the water may be supplied to the deposit through perforations or pores in the collecting or receiving electrodes, which may, for example, be formed as porous walled flues, the water being supplied to the outside of said flues and seeping through the pores thereof so as to penetrate the deposit; or steam may be supplied to the gases containing the suspended materials either before or during their passage through the electrical field, and the collecting or receiving electrodes may be maintained sufficiently cool to cause condensation of water on the deposit. Where practicable, it is desirable to maintain the temperature of the collecting electrode below 100° C. when the process is being carried out under ordinary atmospheric pressure so as to insure condensation of moisture in or on the deposit. In some cases, however, even when working at a high temperature, it is possible to precipitate and maintain sufficient moisture in or on the deposit by supplying water thereto faster than it can be evaporated—for example, in some cases, it is sufficient to spray or inject water into the intake end of the precipitating chamber, or flue, at such a rate and in such quantity that part of the water is precipitated in the form of spray on the deposit before it has had time to evaporate.

Other methods of applying my invention depend on the precipitation, together with the deposit, of a conducting solid material, such as carbon or metallic particles which are supplied to the gases in sufficient quantity to render the deposit precipitated on the collecting electrodes slightly conducting.

Another way of rendering a deposit conducting is to supply to the gases containing suspended particles, suitable reagents which will react either with the gases, or with the suspended particles to form substances which are sufficiently conducting to render the deposit as a whole, more or less conducting.

The accompanying drawings illustrate several forms of apparatus, suitable for carrying out my invention, and referring thereto,—

Figure 1 is a vertical section of a precipitating apparatus in which water is sprayed into the gas to be treated.

Fig. 2 is a section on line 2—2 in Fig. 1.

Fig. 3 is a partial vertical section of a form of the invention in which water is supplied through a perforated discharge electrode.

Figs. 4 and 5 are partial vertical sections of forms of discharge electrode, especially adapted for supply of water therefrom.

Fig. 6 is a vertical section of a precipitating apparatus provided with means for supplying moisture to the deposit through perforations in the collecting electrode.

Fig. 7 is a similar view of an apparatus in which water is supplied through a porous collecting electrode.

Fig. 8 is a horizontal section of a multiple flue construction.

In Fig. 1, and elsewhere, I have shown my invention as applied in connection with the operation of a treater or precipitator having a single pipe or flue, but it will be understood that it is applicable in connection with any of the usual forms of electrical precipitators, whether of the so-called multiple pipe form, or of the form in which the collecting electrodes consist of plates or screens.

Referring to Fig. 1, the collecting electrode 1 is shown as a vertical flue, of cylindrical or other suitable shape and provided, for example, at its upper end, with a chamber or header 2, into which leads a flue 3 for supplying the gas to be treated. The electrode flue 1 may be provided at its lower end with a suitable chamber or header 12 communicating with an outlet flue 13. If desired, the apparatus may be arranged for upward flow of the gases. Suitable means, such as hammer device 15 may be provided for dislodging the deposit from the receiving electrode and causing it to fall into a collecting bin 11, from which it may be removed by screw conveyer 9 or other means.

A discharge electrode 4 is mounted axially in electrode flue 1 and may consist of a wire suspended from an insulated support 5 and tensioned by means of a weight 6 at its lower end. Any other suitable form of discharge electrode may be used.

A water supply means is provided at the upper end of the electrode flue 1, and also, preferably, at one or more levels below the upper end, such water supply means consisting, for example, of nozzles 7 opening tangentially or obliquely into the electrode flue and adapted to receive water from a suitable supply pipe 8, and to deliver such water in the form of spray into electrode flue 1. Similar nozzles 16 and 17 may be provided in the inlet header 2 and in the inlet flue 3. Electrode flue 1 is preferably grounded as indicated at 10' and discharge electrode 4 may be connected by wire 10 to suitable means for supplying high tension unidirectional current, for example, in the manner set forth in patent to F. G. Cottrell, No. 895,729, dated August 11, 1908.

In the operation of the invention as carried out in this apparatus, the gas to be treated is passed downwardly through the collecting electrode or flue 1, and suitable high tension unidirectional current is supplied to the electrodes in such manner as to cause fume or dust suspended in the gas to be precipitated, by the action of the electrical field, on the collecting electrode 1. The gas to be treated is generally a hot furnace

flue gas, and in such case, water may be supplied thereto in the form of steam or in the form of fine spray in such quantity as to be converted wholly or partly into vapor, such supply of water or steam being effected in 70 the supply flue 3 by nozzle 17, in the inlet header 2 by nozzle 16, or in the collecting electrode, by nozzle 7. By radiation from the collecting electrode, or by the cooling effect of injected water, a portion of the water 75 vapor so formed or supplied, is condensed on the solid fume or dust particles, or otherwise, and is precipitated together with such particles so that the resulting deposit is conducting. A cloud or mist of liquid particles 80 may be also produced within the precipitating chamber, by direct atomization of water, and may be precipitated with the fume or dust to render the latter conducting.

In case the gas is not hot, the water may be 85 supplied thereto in the form of steam, and may be condensed to form of a mist by the cooling action of the gas. In any case, the supply of water in liquid or vapor form may be just sufficient to slightly moisten the 90 deposit. Thus, I have found that zinc oxid fume, which, as it is deposited from hot zinc smelter or furnace gases, is an extremely poor conductor, may be made sufficiently 95 conducting to maintain effective precipitation by applying thereto about one per cent. of water.

The nozzles 7, etc., may be used to inject any other suitable agent for making the deposit conductive, such as a finely divided 100 conducting material—for example, oxid of iron, or a chemical reagent capable of acting on a constituent of the gas or fume to form a conducting material. For example, in case lead sulfate is being precipitated, hydrogen sulfid gas may be supplied to the flue 105 gases, so as to convert the lead compound to lead sulfid, which is more conducting than the sulfate.

As shown in Fig. 3, the discharge electrode may be formed as a pipe 20 having perforations 21 whereby water may be supplied to the gas within the treater from a suitable source, such as a tank 23 mounted on the insulated support 24 for said electrode. The collecting electrode 19 may, in this case, be of any usual or suitable construction. The perforated pipe constituting the discharge electrode may be covered with a porous sleeve 25, as shown in Fig. 4. Or, 110 as shown in Fig. 5, the discharge electrode may be formed as a wire or rod 26, covered, if necessary, with a porous jacket 27, and water may be supplied to the upper end of 115 said wire from a water dropping device 28. 120

The water for moistening the deposit may also be supplied through the receiving electrode, as shown in Fig. 6, wherein the receiving electrode 30 is provided with perforations 31, through which water is supplied 130.

from troughs or conduits 32, communicating with a supply pipe 33, said perforations being arranged to deliver water at one or more levels in the receiving electrode, in such manner as to distribute the water throughout the deposit on the electrode. The material may be washed off of the electrode when required, by momentarily increasing the amount of water supplied, in the material so washed off being withdrawn through funnel 35 and outlet 36 at the bottom of the apparatus; or, if desired, the material may be removed by mechanical knocking means of usual type as above explained in connection with Fig. 1.

As shown in Fig. 7, the collecting electrode or flue, indicated at 39, may consist of a cylinder of porous material, such as terra cotta, built up in sections if desired, and extending within an outer cylindrical casing 40, forming a water chamber 41, to which water is supplied through pipe 42, so that the wall of electrode 39 will be kept wet by the water seeping from the water chamber 41, and the deposit collecting on said wall will be kept moist and conducting by absorbing water from said wall. The construction and operation may otherwise be substantially the same as in Fig. 1, and any suitable means may be employed for removing the deposit, when required. For example, a man hole 43 may be provided in the upper header 44 for collecting electrode 39, to enable cleaning the latter by washing with a hose, or by suitable scraping means, the material falling into a lower header 46, from which it is removed through outlet 47. As shown in Fig. 8, any desired number of porous walled collecting electrodes or flues 48 may be mounted in a single outer casing 49, from which water is supplied to all the said flues.

What I claim is:—

1. In the art of electrical precipitation of suspended solid material from gases, the method of maintaining the dielectric strength of the precipitating electrical field in cases where the precipitated material is non-conducting and tends to accumulate a charge by the action of the electrical field which consists in applying to the deposit, an agent capable of increasing the conductivity thereof sufficiently to discharge the same without rendering the deposit fluid.

2. In the art of electrical precipitation of non-conducting solid materials suspended in gases which consists in passing said gases between discharge and collecting electrodes, applying to said electrodes unidirectional current of sufficiently high tension to cause precipitation of said particles on collecting electrodes and continuously applying to the deposit formed on collecting electrodes a conducting substance in sufficient quantity to render the deposit conducting and prevent

the accumulation of a charge on the deposit 65 without rendering the deposit fluid.

3. In the art of precipitating from gases, particles of non-conducting solid material suspended therein, the method of maintaining the dielectric strength of the electrical field and maintaining the maximum possible field strength which consists in continually discharging the deposit, so as to prevent the accumulation of a charge thereon, by applying to the deposit an agent capable of increasing its conductivity without rendering the deposit fluid.

4. In the art of precipitating suspended solid particles from gases by the action of an electrical field, the method of maintaining the conductivity of precipitated material to prevent the accumulation of an electric charge thereon, which consists in supplying water to the gases in such a manner that it is distributed in the form of vapor 80 in the gases and then cooling the gas so as to condense the water vapor and precipitating the condensed water together with the solid particles suspended in the gas.

5. In the art of electrical precipitation 90 from gases of suspended, finely divided, solid material, tending to form a non-conducting, porous deposit and to produce local ionization on such deposit, with resulting lowering of the dielectric strength of the 95 electrical precipitating field, the method of maintaining such dielectric strength which consists in applying to the deposit a conducting material in sufficient quantity to prevent accumulation of electrical charge thereon without rendering the deposit fluid.

6. In the art of electrical precipitation from gases of suspended, finely divided, solid material, tending to form a non-conducting, porous deposit and to produce local 105 ionization on such deposit, with resulting lowering of the dielectric strength of the electrical precipitating field, the method of maintaining such dielectric strength which consists in applying to the deposit a conducting material in sufficient quantity to prevent accumulation of electrical charge thereon, the conducting material being supplied to the gases and precipitated along with the non-conducting deposit.

7. In the art of electrical precipitation of suspended particles from gases, the method of maintaining the dielectric strength of the electrical precipitating field in cases when the precipitated material presents portions 120 of such configuration and non-conducting nature as to cause local ionization by accumulated electrical charge, which consists in applying sufficient conducting material to the precipitated material to prevent the accumulation of electrical charges on such portions without rendering the deposit fluid.

8. The process of separating from gases

- suspended material tending to form a non-conducting deposit, which consists in humidifying such gases and then passing the gases through an electrical field in which an 5 electrical discharge is maintained to cause electrical precipitation of the suspended material and maintaining the precipitated deposit at sufficiently low temperature to cause condensation of water from the gases 10 so as to form sufficiently conducting deposit to prevent accumulation of electric charge thereon.
9. The process of separating from gases suspended solid material tending to form a 15 non-conducting deposit, which consists in supplying water vapor to the gases and then passing the gases through an electrical field maintained between discharge and collecting electrode surfaces to precipitate the suspended 20 material on such collecting electrode surfaces by electrical action and maintaining such collecting electrode surfaces sufficiently cool to cause condensation of water vapor on the deposit and thereby render the 25 deposit sufficiently conducting to prevent the accumulation of electric charge thereon.

10. The process of separating from gases suspended material tending to form a non-conducting deposit, which consists in supplying water to the gases in such manner 30 that water vapor becomes distributed in the gases, passing the gases through an electrical field between discharge and collecting electrodes to precipitate suspended material by electrical action on the collecting electrodes 35 and subjecting the gases to sufficient cooling action to cause condensation of water vapor on the precipitated deposit sufficient to prevent accumulation of electrical charge thereon, the amount of water so supplied to the precipitated deposit being insufficient to form a fluid deposit, and then removing the precipitated deposit from the collecting electrodes.

In testimony whereof I have hereunto set 45 my hand at Los Angeles, Calif., this 27th day of June, 1917.
